DOOR LOCK

Carl A. Hillgren, Huntington Park, Calif.

Application May 9, 1949, Serial No. 92,107

13 Claims. (Cl. 70—147)

1

My present invention relates to a door lock particularly adapted for outside doors.

One of the principal objects of this invention is to provide a door lock, or lock structure, which may be easily installed in doors of varying thickness without the requirement of great accuracy in fitting, and also a lock structure in which the separate units are self-contained and may be easily and quickly assembled within the door from the various sides thereof to provide the complete lock.

Another important object of this invention is to provide a lock structure in which the separate units, to be assembled into the complete lock, are sturdy of construction and may not be readily disassembled, or will not readily get out of order.

An important object also of this invention is to provide a lock structure of this class having three separate and separately controllable latch-operating spindles, all of which terminate at and are arranged to move or operate a single latch or bolt means.

A further important object of this invention is to provide a lock which as a whole is relatively simple, economical, and novel of construction.

With these and other objects in view, as will appear hereinafter, I have devised a door lock having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a transverse sectional view through a door with my door lock in a preferred form mounted thereon;

Fig. 2 is a sectional view taken through the middle portion of a fragmentary portion of the lock in the same position as shown in Fig. 1;

Figs. 3 and 4 are transverse sectional views of the lock taken respectively on the lines 3—3 and 4—4 of Figure 2;

Fig. 5 is an exploded perspective view of the principal elements of the knob and spindle portions of the lock, shown in Figs. 1 to 4;

Figure 6 is a fragmentary perspective view of the inner end of the outer door knob assembly.

Fig. 7 is a perspective view of the locking element, the view being taken from the opposite side from that shown in Fig. 5.

My door lock in a preferred form, as shown in the drawings, is arranged in three separate units or assemblies, which are hereinafter referred to as the bolt or latch assembly A, the outer door

2

knob unit B, and the inner door knob unit C. They are thus arranged so that they may be readily mounted and assembled within the door D.

5 The door is provided with a horizontal bore D¹ extending inwardly from its outer edge for receiving and locating the bolt or latch assembly A. The housing 1 of the bolt or latch assembly is provided at its outer end with a plate 2 which is adapted to be positioned in a recess D² at the outer end of the bore D¹. The plate 2 may be secured in this recess by screws 3. The door has a transverse bore D³ for receiving and locating the mechanism of the lock.

10 As shown, the outer door knob unit has at its inner end a cage 11 which fits into the bore D³ from the outer side of the door, and it has at one side a longitudinal slot formed between ledges 11^a which are adapted to fit into a pair of parallel slots 1^a at the upper and lower sides of the inner end of the housing 1, for locking the cage 11 with respect to the housing 1. These ledges 11^a may slide into the slots 1^a from the outer side of the door. The cage 11 has an escutcheon plate 12 at 15 its outer side which is positioned against the outer side of the door. The outer knob 13 has an inwardly and axially extending hub 14 which is rotatably mounted within the escutcheon plate 12 and is rotatably retained with respect to the escutcheon plate by an arcuate key portion 12^a, as shown in Figs. 2 and 4.

20 The inner knob unit C consists of a knob 51 having a hub 51^a, from the inner end of which axially and non-rotatably extends an inner spindle 52. The portion of the spindle 52, immediately inwardly from the hub 51^a, has a reduced portion 52^a which extends through and is rotatably mounted on an inner escutcheon plate 53, which is positioned against the inner side of the door D and is secured to the inner end of the cage 11 by means of screws 54.

25 In the housing 1 of the bolt or latch assembly A is mounted a bolt 4 and a bolt-actuating member 5, the former extending beyond the plate 2 of the housing 1 and the latter beyond the rear end of the housing. The bolt 4 and actuating member 5 are so arranged that as the actuating member 5 is forced outwardly the bolt 4 is drawn inwardly, such reverse movement being effected by a rocker 6. The bolt 4 is forced outwardly by the spring 7 acting against the actuating member 5. The construction of the bolt unit or assembly is more specifically illustrated and described in my co-pending patent application Serial No. 608,160 of which this is a continuation-

in-part, said co-pending patent application having since issued as Patent No. 2,544,959.

The inner end of the actuating member 5 has flanges or ears 5^a and 5^b which extend laterally in opposite directions, as shown in Figs. 1 and 2, for both restricting and facilitating the outward forcing of the actuating member 5 and the withdrawing of the bolt 4.

The outer knob unit B, which is best illustrated in the exploded view of Fig. 5, carries two spindles, designated spindle member 15 and lock-operated spindle 16, the spindle 16 being broadly a key actuatable member. The spindle member 15 is non-rotatable with respect to the outer knob 13. The spindle member 16 is rotatable relative to both the spindle member 15 and to the outer knob.

The spindle member 15, shown in perspective in Fig. 5, is semi-circular in cross-section, but has in its flat side, or in its flat face, semi-circular recesses 15^a and 15^b in which are positioned, respectively, a latch-operating portion 16^a of the lock-operating spindle 16, of semi-circular cross-section, and also a shank 16^b, the latter being positioned within the semi-circular recess 15^b of the spindle member 15.

The normally outer end of the spindle member 15 extends into a longitudinal channel 14^a, of semi-circular cross-section, in the hub 14 for locking the spindle member and the hub non-rotatably with respect to each other. The outer end of the spindle member has a circumferential groove 15^c in which is positioned a retaining ring 17 for locking the spindle member against movement axially inwardly within the hub of the outer knob, the ring 17 bearing against a semi-circular shoulder 14^b within the hub.

The knob and spindle member are assembled with the cage by inserting the hub of the knob through the escutcheon plate from the outside and by inserting the spindle member through the cage and escutcheon plate from the inside.

On the wall of the opening through the escutcheon plate there is formed the inwardly extending arcuate key portion or keying flange 12^a and a slot 12^b extends through the key portion. The inner end of the hub is also provided with a key portion 14^c and this last identified key portion is adapted to slide through the slot 12^b when the hub is inserted in the opening. When the hub is thereafter rotated 45 degrees, the key portion 14^c will be locked behind the key portion 12^a. A circumferential groove 14^d at the inner end of the hub and adjacent the key portion 14^c receives the key portion 12^a in assembled position.

At the time the hub 14 is inserted through the escutcheon plate from the outside the outer end of the spindle member is extended through the escutcheon plate from the inside and at the same time is extended into the hub. A lug 15^d protrudes laterally outwardly from the convex side of the spindle member. When the spindle member is pushed as far in as it will go, the lug 15^d will abut the inside face of the escutcheon plate and also the inside wall of the keying portion 12^a which is flush with the face. Therefore, when the retaining ring 17 is snapped into place, the ring 17 and lug 15^d will hold the spindle member against endwise movement in the hub.

Since the semi-circular end of the hub 14 and the adjacent semi-circular end of the spindle member are of the same radius, longitudinal edges of the hub will bear against corresponding edges of the spindle member when assembled, as best seen in Figure 4. The knob, hub and spindle

member assembly consequently rotate as a unit.

A locking member 18 is reciprocally mounted in a transverse direction in a channel 11^b at the end of the cage 11 adjacent the escutcheon plate 5. The channel 11^b extends continuously through the longitudinal opening provided between the longitudinal ledges 11^a. The opposite sides of the locking member 18 have lugs 18^b which slide in channels 11^c within the walls of the channel 11^b. In the channels 11^c are located compression springs 19, the ends of which engage the lugs 18^b and normally urge the locking member in a direction toward the right, when viewed, as shown in Fig. 5, or to the side opposite the one having the longitudinal opening between the ledges 11^a.

The locking member 18 has a hollow lateral extension 18^c at the side opposite the portion 18^a. This hollow portion 18^c is best shown in Fig. 7. At the inner side of the hollow portion 18^c is a locking lug 18^d which is normally urged by the springs 19 to enter, from the radially outer side, a recess 14^e located within the key portion 14^c of the hub. Thus, in its normal position, the locking member 18 prevents the outer knob 13 from rotating.

In the cage 11 is provided a hole 11^e. This hole is parallel to the axis of the cage and is located at the side opposite the opening between the ledges 11^a. In this hole is reciprocally mounted a locking plunger 20, the outer end of which extends through a hole 53^a in the inner escutcheon plate 53. The locking plunger is normally urged outwardly from the hole 11^e by a spring 21, the spring engaging a shoulder 20^a on the plunger 20 which is limited by a shoulder or upset portions 11^f at the outer end of the hole 11^e. Near the inner end, and at one side of the plunger, is provided a transverse slot 20^b, the portion immediately inwardly from the slot providing a seat 20^c which normally engages the outer side of the cross portion 18^a of the locking member and holds the same against the compression of the springs 19. When the plunger 20 is pressed inwardly from the inner side of the door, that is, when it is pressed toward the outer side of the door, the slot 20^b is forced opposite the cross portion 18^a, and the springs 19 urge the locking member into the slot 11^b and the lug 18^d into the recess 14^e, thereby locking the outer knob against rotation. When the cross portion 18^a enters the slot 20^b of the plunger 20, the latter is held in its inward position against the action of the spring 21 until it is released from the outside of the door by the lock-operated spindle 16.

The outer end of the lock-operated spindle is rotatably mounted axially within a cage 22 which contains lock-operating tumblers, not shown. Such tumbler arrangement for the lock is shown in Patent No. 2,544,959. The cage has diametrically opposed wings 22^a which extend into conforming recesses (not shown) within the outer knob 13 to lock the cage 22 against rotation with respect to the outer knob. The cage 22 has at its outer side a plate 22^b which serves as a cover for the recess at the axially outer side of the outer knob 13 in which the cage 22 is located.

To facilitate the insertion of the lock-operated spindle 16, the spindle is rotated in a locked position with respect to the cage 22, as shown by dotted lines in Fig. 5. The latch-operated portion 16^a, which is of semi-circular cross-section, is then inserted through the axial opening of the hub and with the flat portion of the latch-operating portion 16^a against the flat face of the spindle

member 15. The inner end of the latch-operating portion 16^a is bevelled, as indicated at 16^c, which engages the cross portion 18^e of the locking member 18 and forces the locking member slightly against the compression springs 19. Such slight shifting of the locking member 18 permits the latch-operating portion 16^a to enter the rectangular recess 18^f of the locking member. This permits the key-operated spindle to be rotated in either direction, and permits the latch-operating portion 16^a to enter the semi-circular recess 15^a of the spindle member, and thereby shifting the shoulder 16^d at the outer end of the latch-operating portion 16^a to engage the shoulder 15^e between the adjacent ends of the recesses 15^a and 15^b, thereby holding the latch-operating spindle in position.

As hereinabove described, the flange or ear 5^a is located between the cross portion 18^e and the flat sides of the spindle member 15 and latch-operating portion 16^a of the key-operated spindle so that the bolt 4 may be withdrawn by rotating the key-operated spindle at all times, and also by rotating the outer knob 13 when the key or lug 18^d is disengaged from the hub of the outer spindle.

After the locking member 18 has been shifted to locking position, which position is illustrated in Figure 2, it may be released therefrom in one of two ways. One way is to rotate the inner knob 51 and the other is to manipulate the key-operated spindle by means of the key. When the inner knob 51 is rotated, the spindle attached thereto and a latch-operating portion 52^b moves against the latch bolt actuator or actuating member 8, shifting it in a direction from right to left as viewed in Figures 2 and 4. Rotation of the key-operated spindle also can be employed to shift the latch-actuating member 8 in a direction from right to left. In either event the actuating member and particularly the ear 5^a thereof is moved against the cross piece 18^e of the locking member 18, shifting that member in a direction from right to left, as viewed in Figures 2 and 5, a distance sufficient to move the lug 18^d out of the recess 14^e located in the key portion 18^c of the hub 14. When the locking member has been moved from right to left, the cross piece 18^a will be lifted clear of the slot 26^b in the plunger 20. When this has been accomplished the spring 21 will shift the plunger 20 in a downwardly direction, as viewed in Figure 2, until it reaches its outermost position stopped by the shoulder 20^a. In the new downward position a seat 26^c on the plunger will then be located beneath the cross piece 18^a, thereby preventing the locking member from being shifted from left to right. Hence the door remains unlocked or unlatched until the next occasion when the plunger 20 is depressed.

The spindle 52 extending axially from the inner knob 51 has the latch-operating portion 52^b, which is also of semi-circular cross-section, and this latch-operating portion is inserted into the inner end of the cage 11 and against the other flange or ear 5^b. When so inserted into the cage 11, the latch-operating portion 52^b is also inserted into and rocks within the recess 15^a of semi-circular cross-section. The inner knob 51 may at all times operate the latch by withdrawing the bolt 4 when the inner knob is rotated. From the inner side of the door, however, the outer knob may be prevented from rotating by forcing inwardly the spring pressed plunger 20.

I wish it to be understood that I do not desire to be limited to the exact details of construction

5
6
shown and described, for obvious modifications will occur to a person skilled in the art.

I claim:

1. In a lock structure, an outer knob, an inner knob, a spindle coaxially and non-rotatably connected to the outer knob and provided at its inner end with a portion of semi-circular cross-section, there being provided, in the plane face of the semi-circular cross-section of said spindle, concentric semi-circular recesses positioned end to end, one at the extended end of the spindle and the other outwardly thereof, the former being of greater diameter, a key-operated spindle located coaxially within the outer knob and coaxially with and rotatable relative to the first spindle, the key-operated spindle having a latch-operating portion located within the larger recess of the first spindle, and also having a shank connecting the latch-operating portion with the outer knob, the shank being located within the smaller recess, the latch-operating portion of the key-operated spindle being also of semi-circular cross-section with the plane face thereof located normally substantially within the plane of the corresponding face of the first spindle, and a third spindle non-rotatably secured at one end to the inner knob and provided at its inner end with a latch-operating portion of semi-circular cross-section lying within the larger recess of the first spindle and with the face of the former located normally substantially within the plane of the corresponding face of the first spindle.

2. In a lock structure, a cage adapted to be fitted in a door, a knob rotatably mounted on the cage and adapted to extend from one side of the door, a spindle extending from the knob into the cage and forming with the knob a rotatable knob assembly, a locking member slidably mounted within the cage in a direction transverse to the axis of the spindle, said spindle extending through said locking member, said spindle being provided with a portion of semi-circular cross-section and provided in the plane face of the semi-circular cross-section with concentric semi-circular recesses positioned end to end, one at the extended end of the spindle and the other adjacent the knob and of less diameter than the former recess, a key-operated spindle located coaxially within the knob and coaxially with and rotatable relative to the first spindle, the key-operated spindle having a latch-operating portion located within the larger recess of the first spindle and having a shank, extending through the smaller recess, connecting the latch-operating portion with the knob, the latch-operating portion of the key-operated spindle being also of semi-circular cross-section with the plane face thereof located normally substantially within the plane of the corresponding face of the first spindle, a latch housing extending from the cage, bolt means mounted in the latch housing and having at its inner end a portion extending between the locking member and the plane faces of the spindles, said locking member having lug means normally in disengaged relationship with the knob assembly, and longitudinally reciprocating means in the cage extending to the opposite side of the door having one position holding the lug means in said disengaged relationship with said knob assembly and having another position wherein the locking member is released for engagement with said knob assembly.

3. In a lock structure, a cage adapted to be fitted in a door, a knob rotatably mounted on the cage and adapted to extend from one side of the

door, a spindle in non-rotatable engagement with the knob and extending from the knob into the cage and forming with the knob a knob assembly, a locking member slidably mounted within the cage in a direction transverse to the axis of the spindle, said spindle extending through said locking member, said spindle being provided with a portion of semi-circular cross-section and provided in the plane face of the semi-circular cross-section with concentric semi-circular recesses positioned end to end, one at the extended end of the spindle and the other adjacent the knob and of less diameter than the former recess, a key-operated spindle located coaxially within the knob and coaxially with and rotatable relative to the first spindle, the key-operated spindle having a latch-operating portion located within the larger recess of the first spindle and having a shank, extending through the smaller recess, connecting the latch-operating portion with the knob, the latch-operating portion of the key-operated spindle being also of semi-circular cross-section with the plane face thereof located normally substantially within the plane of the corresponding face of the first spindle, a latch housing extending from the cage, bolt means mounted in the latch housing and having at its inner end a portion extending between the locking member and the plane faces of the spindles, said locking member having lug means adapted to assume an interlocked relationship with the knob assembly, spring means normally urging the locking member and knob assembly in interlocking relation, catch means having a position of engagement with the locking member enabling a shifting of the lug means of the locking member to a position in engagement with said knob assembly to prevent rotation of the knob assembly, said key-operated spindle being operable to shift the locking member transversely whereby to effect disengagement of said lug means and release of the catch means from engagement with said locking member, and a spring adapted to urge said catch means to a position for holding the lug means of said locking member out of engagement with the knob assembly.

4. In a lock structure, a cage adapted to be fitted in a door, an outer knob rotatably mounted on the outer side of the cage and adapted to extend from the outer side of the door, a spindle extending from the outer knob into the cage, said spindle being provided with a portion of semi-circular cross-section and provided in the plane face of the semi-circular cross-section with concentric semi-circular recesses positioned end to end, one at the inwardly extended end of the spindle and the other adjacent the outer knob and of less diameter than the former recess, a key-operated spindle located coaxially within the outer knob and coaxially with and rotatable relative to the first spindle, the key-operated spindle having a latch-operating portion located within the larger recess of the first spindle and having a shank, extending through the smaller recess, connecting the latch-operating portion with the outer knob, the latch-operating portion of the key-operated spindle being also of semi-circular cross-section with the plane face thereof located normally substantially within the plane of the corresponding face of the first spindle, a latch housing operatively associated with the cage, bolt means mounted in the latch housing and having at its inner end a portion extending to a location adjacent the plane faces of the spindles, an escutcheon plate at the inner side of the cage

for engaging the inner side of the door, an inner knob rotatably mounted on the escutcheon plate, and another spindle non-rotatably secured at one end to the inner knob and provided at its inner end with a latch-operating portion of semi-circular cross-section lying also within the larger recess of the first spindle and with the plane face of the latter latch-operating portion located normally substantially within the plane of the corresponding face of the first spindle.

5. In a lock structure, a cage adapted to be fitted in a door, an outer knob rotatably mounted on the outer side of the cage and adapted to extend from the outer side of the door, a spindle extending from the outer knob into the cage and forming with the knob a knob assembly, a locking member slidably mounted within the cage in a direction transverse to the axis of the spindle, said spindle extending through said locking member, said spindle being provided with a portion of semi-circular cross-section and provided in the plane face of the semi-circular cross-section with concentric semi-circular recesses positioned end to end, one at the inwardly extended end of the spindle and the other adjacent the outer knob and of less diameter than the former recess, a key-operated spindle located coaxially within the outer knob and coaxially with and rotatable relative to the first spindle, the key-operated spindle having a latch-operating portion located within the larger recess of the first spindle and having a shank, extending through the smaller recess, connecting the latch-operating portion with the outer knob, the latch-operating portion of the key-operated spindle being also of semi-circular cross-section with the plane face thereof located normally substantially within the plane of the corresponding face of the first spindle, a latch housing associated with the cage, bolt means mounted in the latch housing and having at its inner end a portion extending between the locking member and the plane faces of the spindles, an escutcheon plate at the inner side of the cage for engaging the inner side of the door, an inner knob rotatably mounted on the escutcheon plate, another spindle non-rotatably secured at one end to the inner knob and provided at its inner end with a latch-operating portion of semi-circular cross-section lying also within the larger recess of the first spindle and with the plane face of the latter latch-operating portion located normally substantially within the plane of the corresponding face of the first spindle, said locking member having lug means normally adapted to assume an interlocked relationship with the knob assembly, and means adjacent the inner knob for holding the lug in disconnected position from the knob assembly.

6. In a lock structure, a cage adapted to be fitted in a door, an outer knob rotatably mounted on the outer side of the cage and adapted to extend from the outer side of the door, a spindle in non-rotatable engagement with the knob and extending from the outer knob into the cage, said spindle and said knob forming a knob assembly, a locking member slidably mounted within the cage in a direction transverse to the axis of the spindle, said spindle extending through said locking member, said spindle being provided with a portion of semi-circular cross-section and provided in the plane face of the semi-circular cross-section with concentric semi-circular recesses positioned end to end, one at the inwardly extended end of the spindle and the other adjacent the outer knob and of less diameter than the

former recess, a key-operated spindle located coaxially within the outer knob and coaxially with and rotatable relative to the first spindle, the key-operated spindle having a latch-operating portion located within the larger recess of the first spindle and having a shank, extending through the smaller recess, connecting the latch-operating portion with the outer knob, the latch-operating portion of the key-operated spindle being also of semi-circular cross-section with the plane face thereof located normally substantially within the plane of the corresponding face of the first spindle, a latch housing associated with the cage, bolt means mounted in the latch housing and having at its inner end a portion extending between the locking member and the plane faces of the spindles, an escutcheon plate at the inner side of the cage for engaging the inner side of the door, an inner knob rotatably mounted on the escutcheon plate, another spindle non-rotatably secured at one end to the inner knob and provided at its inner end with a latch-operating portion of semi-circular cross-section lying also within the larger recess of the first spindle and with the plane face of the latter latch-operating portion located normally substantially within the plane of the corresponding face of the first spindle, said locking member having lug means adapted to assume an interlocked relationship with the knob assembly, spring means normally urging the locking member into interlocking relation with the knob assembly, a reciprocating catch means having a latching position enabling the shifting of the lug means of the locking member to a position in engagement with said knob assembly to prevent rotation thereof, said key-operated spindle being arranged to cause transverse movement of the locking member and corresponding retraction of said lug means, said movement of the locking member being adapted to release said catch means, and a spring for urging said catch means to a position for holding said locking member and lug means from engagement with the knob assembly.

7. In a lock structure, a cage adapted to be fitted in a door, a knob rotatably mounted on the cage and adapted to extend from one side of the door, a spindle extending from the knob into the cage and forming with the knob a rotatable knob assembly, a locking member slidably mounted within the cage in a direction transverse to the axis of the spindle, said spindle extending through said locking member, said spindle being provided with a latch-operating face, a key-operated spindle located coaxially within the knob and rotatable relative to the first spindle, the key-operated spindle having a latch-operating portion provided with a face normally coplanar with the former face and provided with a shank connecting the latch-operating portion of the key-operated spindle with the knob, a latch housing extending into and engageable with the cage, bolt means mounted in the latch housing and having at its inner end a portion extending between the locking member and the faces of the spindles, said locking member having lug means normally in disengaged relationship with the knob assembly, and longitudinally reciprocating means in the cage extending to the opposite side of the door having one position adapted to hold the locking member and the lug means in said disengaged relationship with the knob assembly and having another position adapted to release the locking member and the lug means for engagement with said knob assembly.

8. In a lock structure, a cage adapted to be fitted in a door, a knob rotatably mounted on the cage and adapted to extend from one side of the door, a spindle in non-rotatable engagement with the knob extending from the knob into the cage, said knob and spindle forming a knob assembly, a locking member slidably mounted within the cage in a direction transverse to the axis of the spindle, said spindle extending through said locking member, said spindle being provided with a latch-operating face, a key-operated spindle located coaxially within the knob and rotatable relative to the first spindle, the key-operated spindle having a latch-operating portion provided with a face normally coplanar with the former face and provided with a shank connecting the latch-operating portion of the key-operated spindle with the knob, a latch housing extending into and engageable with the cage, bolt means mounted in the latch housing and having at its inner end a portion extending between the locking member and the faces of the spindles, said locking member having lug means adapted to assume an interlocked relationship with the knob assembly, spring means normally urging the locking member into interlocking relation with said knob assembly, catch means having a position enabling the shifting of the lug means of the locking member to a position in engagement with said knob assembly to prevent rotation thereof, said key-operated spindle being arranged to cause transverse movement of the locking member and disengagement of the lug means from the knob assembly and release of the locking member from said catch means, and a spring for urging said catch means to another position for holding said locking member and said lug means from engagement with the knob assembly.

9. In a latch structure a cage having an opening extending longitudinally therethrough and having a laterally open aperture in the wall of the cage communicating with the opening, a latch housing slidably engaging the cage at the edges of the aperture and latch bolt means in the latch housing including a latch bolt actuating member, said actuating member extending from the inside end of the latch housing into the cage, said actuating member having parts thereof extending laterally relative to the axis of the latch housing, a knob in rotatable engagement with the cage, an exteriorly arcuate section on the knob having a key thereon projecting laterally outwardly, said cage having on the wall of the opening therethrough an inwardly projecting arcuate keying flange and said flange having a slot therethrough adapted to receive the key of the knob during assembly, said keying flange being in engagement with the key of the knob in assembled relationship and retaining the knob on the cage, a separate arcuate spindle member having an outer curved side, said spindle member being located in the knob in a position opposite and in engagement with the arcuate section of the knob whereby the spindle is in non-rotatable relationship with the knob, a lug on the outer curved side of the spindle member projecting laterally outwardly and in endwise engagement with a portion of the cage to limit extension of the spindle member into the knob, a rotatable key actuable member in the knob having in assembled condition a position of non-releasable endwise engagement with the spindle member, said latch bolt actuating member having when the latch housing is assembled with the cage a position com-

11

prising a rotation-limiting stop for the spindle member and the key actuatable member whereby the cage, knob, and spindle member are interlocked in assembled relation.

10. In a latch structure a cage having an opening extending longitudinally therethrough and having a laterally open aperture in the wall of the cage communicating with the opening, a latch housing slidably engaging the cage at the edges of the aperture and latch bolt means in the latch housing including a latch bolt actuating member, said actuating member extending from the inside end of the latch housing into the cage, a knob in rotatable engagement with the cage, said knob including a circumferentially extending portion having a longitudinally disposed abutment and a key on said portion projecting laterally outward, said cage having on the wall of the opening therethrough an inwardly projecting arcuate keying flange and having a slot through the flange adapted to have the key extend therethrough during assembly, said key in assembled position being positioned behind the keying flange for retaining the knob on the cage, a separate arcuate spindle received endwise in the knob in position fixed against endwise movement relative to the knob, said spindle having a portion thereof at a location on the knob in opposed relation to the abutment and in non-rotatable relationship with the knob, a cylinder lock in the knob having an axially disposed shank extending therefrom and a latch operating portion on said shank, said shank being freely insertable in the knob in one position of rotation and being in endwise non-releasable engagement with the spindle member throughout other positions of rotation, said latch bolt actuating member having a position of rotation limiting engagement with the spindle member and the latch operating portion of the shank whereby the cage, knob, cylinder lock and spindle member are interlocked in assembled relation.

11. In a lock structure a cage having an opening extending longitudinally therethrough and having a laterally open aperture in the wall of the cage communicating with the opening, a latch housing slidably engaging the cage at the edges of the aperture and latch bolt means in the latch housing including a latch bolt actuator, said latch bolt actuator extending from the latch housing into the cage and extending laterally of the longitudinal axis of the housing, a knob in rotatable engagement with the cage, an arcuate section on the knob having a key extending laterally, said cage having on the wall of the opening therethrough an inwardly projecting arcuate keying flange and having a slot through the flange adapted to receive the key during assembly, said key being located behind the keying flange in assembled position thereby retaining the knob on the cage, a separate arcuate and interiorly recessed spindle member in the knob in a position of engagement with the arcuate section of the knob and in non-rotatable relationship with the knob, an outwardly projecting lug on the spindle member in engagement against the arcuate keying flange whereby to set the position of the spindle member endwise in the knob, a cylinder lock in the knob having an axially disposed shank extending into the cage, said shank having an offset latch operating portion forming an arcuate outwardly facing shoulder, said latch operating portion being freely insertable in the knob during assembly in one position of rotation, an interior shoulder in the spindle member in engage-

12

ment with the shoulder on the shank and retaining said shank throughout other positions of rotation thereof, said latch bolt actuating member having a position when the latch housing is assembled with the cage wherein the latch bolt actuating member comprises a rotation limiting stop for the spindle member and the latch operating portion of the shank whereby the cage, knob, cylinder lock and spindle member are interlocked in assembled relation.

12. In a lock structure a cage, a latch housing, said cage having an aperture receiving the housing, said housing having a slidable connection with the cage at the sides of the aperture and extending laterally outwardly therefrom, latch bolt means in said housing including a latch bolt actuating member and said actuating member extending from the housing into the cage, an outside knob in rotatable engagement with the cage having a spindle non-rotatably fixed thereto and extending into the cage to a position adjacent and in operative relationship with the actuating member, said cage having a transversely extending aperture adjacent the engagement of the outside knob with the cage, a locking member comprising a centrally apertured yoke transversely slidable in said aperture and surrounding the spindle member, a spring between the locking member and the cage adapted to urge the locking member transversely of the cage, transversely engageable detent means in the locking member and the outside knob, respectively, and normally pressed into engagement by said spring, a locking plunger extending from the cage outwardly on the side of the structure opposite said outside knob normally spring pressed to unlocked position having means adapted to engage said locking member in a transversely shifted location when in locked position, an inside knob, and a latch operating portion thereon located adjacent the latch actuating member, said latch actuating member having a transversely disposed portion in a position between the locking member and said latch operating portion adapted upon rotation of said inside knob to disengage the locking member from the outside knob and from the locking plunger.

13. In a lock structure a cage, a latch housing, said cage having an aperture receiving the housing, said housing having a slidable connection with the cage at the sides of the aperture during assembly and the housing extending laterally outwardly from the cage, latch bolt means in said housing including a latch bolt actuating member and said actuating member extending from the housing into the cage, an outside knob in rotatable engagement with the cage having a spindle non-rotatably fixed thereto forming an outside knob assembly, said spindle having a latch operating portion within the cage for actuation of said actuating member, a cylinder lock in the outer knob having a shank anchored thereto and said shank extending into the cage adjacent to the spindle and adapted to rotate relative to the spindle, said cage having a transversely extending aperture adjacent the engagement of the outside knob with the cage, a locking member comprising a centrally apertured yoke transversely slidable in said aperture and surrounding the shank and the spindle, a spring between the locking member and the cage adapted to urge the locking member transversely of the cage, a lug on the locking member and means on the outside knob forming a recess for the lug, said lug comprising a releasable spring pressed engagement

between the locking member and the outside knob assembly, a reciprocating locking plunger extending from the cage outwardly on the side of the structure opposite said outside knob normally spring pressed to unlocked position having a slot adapted to receive a portion of said locking member when in locked position, an inside knob and a latch operating portion thereon located adjacent the latch actuating member, said latch actuating member having a transverse portion in a 10 position between the locking member on one side of said transverse portion and said shank and latch operating portions on the other side of said transverse portion adapted upon rotation of said

inside knob and said cylinder lock to disengage the locking member from the outside knob assembly and from the locking plunger.

CARL A. HILLGREN.
